UNITED STATES PATENT OFFICE

MELBOURNE A. BECKMANN, OF CINCINNATI, OHIO, ASSIGNOR TO HARRY J. HATER,
OF CINCINNATI, OHIO

PISTON

Application filed June 7, 1929. Serial No. 369,131.

My invention relates to improvements in pistons and more particularly to pistons adapted for use in internal combustion engines.

An important object of my invention is the provision of a piston capable of being formed from light weight material such as aluminum, aluminum alloys, magnesium and similar metals in which the undesirable expansion of the piston caused by the relatively high thermal expansion ratio of the light weight material is rendered comparatively ineffective for all practical purposes.

A further object of my invention is the production of a piston so constructed that the heat of combustion, which causes undesirable expansion of the piston skirt, is so diverted and impeded in the course of its transmission from the head of the piston to its skirt, that its influence upon the skirt of the piston is reduced to a minimum.

Another object of my invention is to provide a piston, the construction of which will counteract the thrust forces accruing from the explosion on the head of the piston.

A further object of my invention is to control expansion of the piston so that it will work efficiently at all operating temperatures.

Other objects and advantages of my invention will be apparent during the course of the following description.

This invention is an improvement on the pistons covered by the pending applications 35 227,705 filed October 21, 1927, and 326,832 filed December 18, 1928, by Stephen D. Hartog.

In the accompanying drawings, which form a part of this specification and wherein like characters of reference denote like or corresponding parts throughout the same,

Figure 1 is a side elevation of my improved piston,

Figure 2 is an elevation of the opposite side thereof,

Figure 3 is a vertical sectional view on the line 3—3 of Figure 1,

Figure 4 is a horizontal sectional view on the line 4—4 of Figure 1, and

Figure 5 is a bottom plan view of the piston.

In the drawings, wherein for the purpose of illustration is shown a preferred embodiment of my invention the numeral 10 designates the head of the piston having a depending rim 11 provided with a series of ring grooves 12 to receive suitable packing rings, not shown. The skirt 13 of the piston is separated from the head 10 and rim 11 by a circumferentially extending opening 14. The piston skirt is relieved by being completely cut away at diametrically opposite points, and said cutaway portions 15 and 16 extend from points spaced from the bottom of the skirt to the opening 14.

Piston pin receiving hubs or bosses 17 and 18 are arranged in the cutaway portions 15 and 16 respectively and are located substantially centrally thereof. The hubs 17 and 18 are provided with the usual bores 19. The outer end of the hub 17 is connected to the portions of the skirt at the sides of the cutaway portion 15 by means of a transverse or horizontal strut 20 arranged above the center 75 of the hub and integrally formed therewith, and with the piston skirt. The outer face of the strut 20 is flush with the outer face of the hub 17 and the ends of the strut 20 have a curvature conforming to the curvature of the adjacent skirt portions and form a continuation thereof, as at 21. A vertical strut 22 connects the outer end of the hub 17 with the portion of the skirt at the bottom of the cutaway portion 15 and is arranged centrally of the cutaway portions and of the hub. The struts 20 and 22 form a T-shaped connection between the outer end of the hub 17 and the piston skirt with the hub arranged at the juncture of the arms of the T. 90

The inner end of the hub 17 is connected to the head of the piston by means of a vertically extending strut 23 arranged centrally of the cutaway portion 15 and outwardly offset at its upper end to join the head. A 95 suitable reinforcing rib 24 connects the hub with the head and extends down the center of the strut 23. The strut 23 extends a short distance below the hub 17 and connects with a transverse strut 25 which is joined at its 100

ends to the sides of the piston skirt adjacent the lower end of the cutaway portion 15. A suitable reinforcement rib 26 extends from the center of the hub 17 to the lower end of the strut 25. The strut 23 merges into an encircling flange 27 on the hub 17 and together with the strut 25 forms an inverted T-shaped connection between the head, piston pin hub and skirt.

10 It will be seen then, that the hub 17 is joined at its outer end to the skirt by the struts 20 and 22, and joined at its inner end to the head and skirt by the struts 23 and 25. At a suitable position between the outer 15 struts 20 and 22 and the inner strut 23 there is an opening 28 dividing the inner end of the hub 17 from the outer end thereof, and said opening 28 may be cut after the piston is cast, but is preferably cast with the piston.

20 When cast with the piston the opening 20 is formed slightly wider at its lower end than at its upper end to facilitate removal of the core member therefrom. The hub 17 is consequently separated by the opening 28 into 25 spaced inner and outer portions, the inner portion being integrally connected with the struts 23 and 25, and the outer portion being integrally connected with the struts 20 and 22, there being no direct connection between 30 the struts 20 and 22 and the struts 23 and 25, or between the separated portions of the hub.

The struts 20 and 22 are, therefore, independent of the struts 23 and 25, and heat 35 passing from the head 10 through the strut 23 will not be conducted to the struts 20 and 22 and the adjoining skirt portions.

The hub 18 is connected to the head of the piston by a vertically arranged strut 23' 40 which extends below the hub and joins with a transverse strut 25' which is joined at its ends to the sides of the piston skirt adjacent the lower end of the cutaway portion 16. The strut 23' merges into an encircling flange 45 27' on the hub 18 and a suitable reinforcing rib 24' connects the head with the hub 18 and extends down the inside of the strut 23'. The struts 23' and 25' have the same position relative to the hub 18 as the struts 23 and 25 50 have to the hub 17, and transverse struts 20' connect the strut 23' with the portions of the skirt at the sides of the cutaway portion 16. The struts 20' are offset outwardly to merge with the skirt at the edge of the cutaway portion 16. The hub 18 is not split as is the hub 17 but is unbroken, and supported by the struts 20', 23' and 25'.

A suitable reinforcement such as 22' may be provided at the lower end of the cutaway portion 16, if desired.

The non-thrust side of the piston skirt is provided with a vertical slit 29 extending from the bottom of the skirt to the opening 14 which separates the head from the skirt, 65 and the thrust side of the skirt is unbroken.

A substantially continuous annular bearing surface is, therefore, provided adjacent the bottom of the skirt and is unbroken except for the single slit 29. The inner portion of the skirt adjacent the slit 25 is provided with 70 reinforcements 30 which parallel the slit and strengthen the separated portions of the skirt. While the slit 29 completely separates the non-thrust side of the skirt, the arrangement of the transverse struts 20, 20', 25 and 25' is sufficient to hold the separated portions of the skirt in position.

In the operation of my improved piston, the head portion is subjected to direct heat generated by the explosion of gases in the combustion chamber, and this heat is conducted away through the integrally connected struts 23 and 23' and through the surrounding metal of the cylinder. The struts 23 and 23' are the only portions of the piston having direct connection with the head, and the only path by which heat may be conducted to the piston skirt. The heat is so reduced when it reaches the bottom of the skirt that it is comparatively ineffective due to the long and circuitous route which it must travel. While the opening 28 in the split hub 17 prevents the travel of the heat directly to the side portions of the skirt, the strut arrangement on the opposite side of the piston is such as to effectively counteract the thrust forces accruing from the explosion on the head of the piston.

While I have shown and described the preferred embodiment of my invention it is 100 to be understood that various changes in the size, shape and arrangement of parts may be resorted to without departing from the spirit of my invention or the scope of the subjoined claims.

Having thus described my invention what I claim and desire to protect by Letters Patent is:

1. A piston comprising a head and skirt, said skirt having a cutaway portion therein spaced from the bottom thereof, a piston pin hub arranged in said cutaway portion, a strut connecting the outer end of said hub with the portion of the skirt at the sides of the cutaway portion, the ends of said strut having a curvature corresponding to the curvature of the piston skirt and forming a continuation thereof.

2. A piston comprising a head and skirt, said skirt being spaced from said head by a circumferentially extending opening, said skirt being provided with a cutaway portion extending from a point spaced from the bottom of said skirt into the circumferential opening, a piston pin hub arranged in said cutaway portion, and a transverse strut connecting the outer end of said hub with the portions of the skirt at the sides of the cutaway portion, the outer face of the strut adjacent its ends having a curvature conforming to 130

the curvature of the skirt and forming a continuation thereof.

3. A piston comprising a head and skirt, said skirt being provided with a cutaway portion spaced from the bottom thereof, a piston pin hub arranged in the cutaway portion and spaced from the sides thereof, and a transverse strut connecting said hub with the portions of the skirt at the sides of the cutaway portion, the outer face of the strut being flush with the outer face of the hub and having a curvature at its ends conforming to the curvature of the skirt and forming a continuation thereof.

4. A piston comprising a head and skirt, said skirt being spaced from the head by a circumferentially extending opening, said skirt being provided with a cutaway portion extending from a point spaced from the bottom thereof into the circumferential opening, a piston pin hub arranged in the cutaway portion and spaced from the sides thereof, a transverse strut connecting said hub with the portions of the skirt at the sides of the cutaway portion, the outer face of the strut being flush with the outer face of the hub and having a curvature at its ends conforming to the curvature of the skirt and forming a continuation thereof, and a strut connecting the piston pin hub to the portion of the skirt at the lower end of the cutaway portion.

5. A piston comprising a head and skirt, said skirt having cutaway portions therein spaced from the bottom thereof, a piston pin hub of integral construction arranged in one of said cutaway portions, struts connecting said hub with the head and skirt of the piston, a piston pin hub in the other cutaway portion, said last named hub being split to form two spaced portions, one of said portions being connected by struts to the skirt, and the other of said portions of the hub being connected by struts with the head and skirt of the piston.

6. A piston comprising a head and skirt, said skirt having cutaway portions therein spaced from the bottom thereof, a piston pin hub of integral construction arranged in one of said cutaway portions, said hub being connected by struts to the head and skirt of said piston, a piston pin hub arranged in the other cutaway portion, said last named hub being split to form spaced portions, a transverse strut connecting the outer portion of said split hub to the portions of the skirt at the sides of the cutaway portion, and the inner end of said split hub being connected by struts with the head and skirt of said piston.

7. A piston comprising a head and skirt, said skirt being separated from the head by a circumferential opening, said skirt being provided with cutaway portions extending from a point spaced from the bottom of the skirt into the circumferential opening, a piston pin hub arranged in one of said cut-

away portions, said hub being split to form spaced portions, the inner portion of said hub being connected to the head and skirt by means of a substantially inverted T-shaped strut, and the outer portion of said hub being connected to the skirt by a substantially T-shaped strut, a piston pin hub of integral construction arranged in the other cutaway portion, said integral hub being connected by struts with the head and skirt of the piston.

8. A piston comprising a head and skirt, said skirt being separated from the head by a circumferentially extending opening, said skirt being provided with diametrically opposed cutaway portions extending from the circumferential opening to a point spaced from the bottom of the skirt, a piston pin hub arranged in one of said cutaway portions substantially centrally thereof, said hub being split to provide spaced portions, a substantially inverted T-shaped strut connecting the inner portion of said hub with the head and skirt, a substantially T-shaped strut connecting the outer portion of said hub to the portions of the skirt at the sides and bottom of said cutaway portion, the upper arm of said T-shaped strut having its outer face flush with the outer face of the piston pin hub and having a curvature at its ends conforming to the curvature of the piston skirt and forming a continuation thereof, a piston pin hub of integral construction arranged in the other cutaway portion, said integral hub being connected by struts with the head and skirt of the piston.

9. A piston comprising a head and skirt, said skirt being separated from the head by a circumferentially extending opening, said skirt being provided with diametrically opposed cutaway portions extending from the circumferential opening to a point spaced from the bottom of the skirt, a piston pin hub arranged in one of said cutaway portions substantially centrally thereof, said hub being split to provide spaced portions, a substantially inverted T-shaped strut connecting the inner portion of said hub with the head and skirt, a substantially T-shaped strut connecting the outer portion of said hub to the portions of the skirt at the sides and bottom of said cutaway portion, the upper arm of said T-shaped strut having its outer face flush with the outer face of the piston pin hub and having a curvature at its ends conforming to the curvature of the piston skirt and forming a continuation thereof, a piston pin hub of integral construction arranged in the other cutaway portion, said integral hub being connected by struts with the head and skirt of the piston.

10. A piston comprising a head and skirt, said skirt being separated from the head by a

circumferential opening, said skirt being provided with a cutaway portion extending from the circumferential opening to a point spaced from the bottom of the skirt, a piston pin hub 5 arranged in said cutaway portion, said hub being split to provide spaced portions, a substantially inverted T-shaped strut connecting the inner portion of said hub with the head and skirt, a substantially T-shaped strut connecting the outer portion of the hub to the 10 portions of the skirt at the sides and bottom of the cutaway portion, the upper arm of said last named T-shaped strut having its outer face flush with the outer face of the piston 15 pin hub and having a curvature at its end, conforming to the curvature of the piston skirt and forming a continuation thereof.

In testimony whereof I affix my signature.
